United States Patent Office

Des. 203,363
Patented Dec. 28, 1965

203,363

LIFE PRESERVER

Hubert H. Crawford, 231 Humboldt Parkway,
Buffalo, N.Y.

Filed Sept. 8, 1964, Ser. No. 81,634

Term of patent 14 years

(Cl. D71—1)

The figure is a front perspective view of a life preserver showing my new design.

The appearance of a life preserver of my design is substantially the same as viewed in side elevation from either side thereof.

I claim:

The ornamental design for a life preserver, as shown and described.
